UNITED STATES PATENT OFFICE.

DAVID DAVIDSON MILLER, OF MIDDLETOWN, CONNECTICUT.

PICKER-MOTION FOR LOOMS.

SPECIFICATION forming part of Letters Patent No. 757,828, dated April 19, 1904.

Application filed October 26, 1903. Serial No. 178,485. (No model.)

To all whom it may concern:

Be it known that I, DAVID DAVIDSON MILLER, a citizen of the United States, residing at Middletown, in the county of Middlesex 5 and State of Connecticut, have invented certain new and useful Improvements in Picker-Motions for Looms; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The object of this invention is to improve the means for operatively connecting a loom picker-stick with its lug-strap, so that adjustment can be readily effected, and to furthermore accomplish this purpose without producing a mechanism which is complicated, cumbersome, expensive to manufacture, troublesome to attach, and liable to jar loose.

In the single figure of the accompanying drawing my invention is shown as operatively applied to a picker-stick and its lug-strap, the whole appearing in front elevation.

In the drawing, *a* is the picker-stick, and *b* the lug-strap, the same having a loop *c*, which embraces the picker-stick. On the edge *d* of the picker-stick which is the farther from the power is secured, as by screws *e* or the like, a bracket consisting of a metallic plate *f*, having its end portions *g* turned off in the same direction at right angles. In this bracket and preferably parallel with the edge *d* of the picker-stick is mounted a rod *h*. On the rod is secured, as hereinafter described, a loop *i*, preferably made of metal and through which the loop *c* of the strap *b* extends. Loop *i* is 40 by preference disposed between the rod *h* and the body part of the bracket *f*, so that under the pull of the strap said loop may take up against the bracket.

I preferably make the rod *h* as a bolt having 45 a head *j*, which takes against the outer face of one of the parts *g* of the bracket, and with two nuts *k*, which take against opposite faces of the other part *g*, and thus clamp the rod securely to the bracket. The rod is threaded 50 more or less to receive the nuts *k* and also so

as to afford means for adjusting the loop *i*, which is preferably secured to the rod by having its ends, which said rod penetrates, clamped between nuts *k*, screwed onto the threaded portion of the rod.

My improved means for operatively connecting the picker-stick and its lug-strap has many advantages, not the least among which is the fact that an indefinite variety of adjustments is possible. It is light and durable in construction, involves relatively little expense to manufacture, and owing to its fewness of parts and general construction is capable of being readily assembled and makes of itself no objectionable projection on the picker- 65 stick.

I do not wish to be limited to the precise construction herein shown and described; but

What I do claim as new, and desire to secure by Letters Patent, is—

1. The combination of the picker-stick, the lug-strap, and means for connecting the lug-strap to the picker-stick so as to be adjustable longitudinally of the latter, said means comprising a bracket secured to the picker-stick 75 and having spaced projecting portions disposed the one above the other, a rod extending longitudinally of the picker-stick and mounted in said projecting portions, and a device directly engaged by the lug-strap and connected to the rod for adjustment longitudinally thereof, said device being disposed between said projecting portions, substantially as described.

2. The combination of the picker-stick the 85 lug-strap, and means for connecting said lug-strap to the picker-stick so as to be adjustable longitudinally of the latter, said means comprising a rod extending longitudinally of the picker-stick, means, engaging said rod at 90 spaced points thereon, for securing said rod to the picker-stick, and a device directly engaged by the lug-strap and connected to the rod for adjustment longitudinally thereof between its points of engagement with said securing 95 means, substantially as described.

3. The combination of the picker-stick, the lug-strap, a threaded rod extending longitudinally of the picker-stick, a bracket having spaced projecting portions arranged the one 100

above the other, said rod being mounted in said projecting portions, a loop receiving the lug-
strap and penetrated by said rod and disposed
thereon between said projecting portions, and
5. nuts engaging the threaded portion of the rod
and clamping said loop between them, substan-
tially as described.

In testimony that I claim the foregoing I
have hereunto set my hand this 22d day of Oc-
tober, 1903.

DAVID DAVIDSON MILLER.
